UNITED STATES PATENT OFFICE.

GEORGE B. POWERS, OF SUPERIOR, WISCONSIN.

TREE HOLDER.

1,422,304.

Specification of Letters Patent. Patented July 11, 1922.

Application filed March 8, 1921, Serial No. 450,698. Renewed January 30, 1922. Serial No. 532,857.

To all whom it may concern:

Be it known that I, GEORGE B. POWERS, a citizen of the United States, residing at Superior, in the county of Douglas and 5 State of Wisconsin, have invented certain new and useful Improvements in Tree Holders, of which the following is a specification.

This invention relates to tree holders and the object is to provide a neat, attractive and 10 novel device for supporting Christmas trees, and to provide illuminated means in connection therewith for displaying the words "Merry Christmas" or other suitable words or designs. The invention is fully described 15 in the following specification and is disclosed in the accompanying drawings, in which:

Fig. 1 is an elevation of the device as set up and in use.

20 Fig. 2 is a view similar to Fig. 1, but with the sign 7 thereof removed.

Fig. 3 is a sectional view on the line 3—3 in Fig. 2, the light 8 and the tree trunk 9 being removed.

25 Fig. 4 is an enlarged detail sectional view on the line 4—4 in Fig. 1.

Fig. 5 is an enlarged detail sectional view on the line 5—5 in Fig. 1.

Fig. 6 is a view showing the device in 30 partly knocked down or folded position.

Referring to the drawings by reference numerals 10 designates the back or main body member of the device, having a hole 11 closed by a lid 12, pivoted at 13. Two 35 end pieces 14, 15 are so hinged to the back 10 by hinges 16 and 17, respectively, that they may fold against it as shown in Fig. 6.

A bottom piece 18, hinged as at 19, is provided with two arms 20 which serve to hold 40 the end pieces in open position. These members are provided at their intersections with a socket 21, which is connected by flexible circuit wires 22, to a socket 23 secured on the back of the member 10. The lamp 8 is 45 placed in the socket 21 when the device is being used and the socket 23 is then connected to a suitable source of electricity through the wires 24 (see Fig. 4). In Fig. 4 is also shown a hook 25 which may be used to hold 50 the arms 20 down. When the device is not in use the bulb 8 and wires 24 are disconnected; the member 18 is swung up and the arms 20 and socket 21 then assume the positions shown in Fig. 6. The tree 9 rests in 55 a recess 26 in the member 18, and extends up through a hole 27 in a cover 28. The cover

28 is hinged at 29 to blocks 30 secured on the back 10, so that when the device is knocked down the cover will fold upon the parts 14, 15, 18 and 20. Each end of the 60 cover 28 is provided with a hinged section 31. These sections 31 rest in the positions as shown in Figs. 1, 2 and 3 when the device is set up, but swing up, as shown in Fig. 6, so that they may be folded down with the 65 cover when the latter is folded down. The tree 9 is clamped in rigid position by two clamping members 32 and 33, the former of which is fixed and the latter of which is pivoted at 34 on the cover 28 adjacent the 70 hole 27. These members 32, 33 are provided with brackets 35 which are connected by a bolt 36, so that when the nut 37 is tightened the tree 9 will be clamped by the members or clamps 32, 33.

75

The cover 28 and the end pieces 14 and 15 are provided with keepers 38, up into which is slid an opaque card 7 having suitable transparent or translucent words or designs 40, as shown in Fig. 1. The cover 12 prevents the light from the bulb 8 from shining through the hole 11, and is swung to one side only when the device is folded up so as to allow room for the socket 21.

It is understood that various suitable 85 modifications may be made in the form and structure of this invention if such modifications come within the spirit and scope of the appended claims.

Having now therefore fully shown and 90 described my invention, what I claim to be new and desire to protect by Letters Patent is:

1. In a device of the class described, a back, a base member having a recess therein 95 hingedly secured to the back, a top piece hingedly secured to the back said top piece having an aperture directly above the recess in the base member, and means for clamping a tree trunk in rigid position in said recess 100 and aperture.

2. In a device of the class described, a back having a hole therein, a base member hingedly secured to the back, a socket on said base member adapted to be folded into 105 said hole, and means for supporting a tree on said base member.

3. A device of the class described consisting of a back member, end members hingedly secured to the back and adapted to fold 110 thereupon, a base member hingedly secured on the back to fold upwardly thereupon, and

a top piece hingedly secured to the back to fold down upon said base and end members, said top and base members having apertures in which may be supported a tree trunk.

5. 4. A device of the class described consisting of a back member, end members hingedly secured to the back and adapted to fold thereupon, a base member hingedly secured on the back to fold upwardly thereupon, 10 arms on said base member adapted to hold the end members open, and a top piece hingedly secured to the back to fold down upon said base and end members, said top and base members having apertures in which 15 may be supported a tree trunk.

5. A device of the class described consisting of a back member, end members hingedly secured to the back and adapted to fold thereupon, a base member hingedly secured 20 on the back to fold upwardly thereupon, and

a top piece consisting of a number of hingedly connected sections hingedly secured to the back to fold down upon said base and end members, said top and base members having apertures in which may be supported 25 a tree trunk.

6. A device of the class described consisting of a back member, end members hingedly secured to the back and adapted to fold thereupon, a base member hingedly secured 30 on the back to fold upwardly thereupon, a top piece hingedly secured to the back to fold down upon said base and end members, said top and base members having apertures in which may be supported a tree trunk, and 35 clamping means for rigidly securing the tree in said apertures.

In testimony whereof I affix my signature.

GEO. B. POWERS.
